INVENTOR.

Emory Parsons

UNITED STATES PATENT OFFICE.

EMORY PARSONS, OF NEWARK, NEW JERSEY.

TIME LIGHTING DEVICE.

Application filed October 17, 1922. Serial No. 595,049.

To all whom it may concern:

Be it known that I, EMORY PARSONS, a citizen of the United States, residing at 304 Montclair Avenue, Newark, in the county 5 of Essex and State of New Jersey, have invented certain new and useful Improvements in Time Lighting Devices.

My invention relates to improvements in a time lighting device; the objects of the improvement are, first, to provide the means for closing a circuit over which electrical energy may flow, at a pre-determined time, and during the absence of the attendant, second, to provide means to indicate the time 15 at which the circuit closing portion of the device will operate. My invention may be used in service in which electric power, or illuminating electric lights, or signal electric lights, is or, are required to become operative 20 at a time when no attendant is present, but it is designed primarily for use in closing, during the absence of the driver, the electric light circuit which controls the standing, or parking, lights ordinarily found on motor 25 driven vehicles.

My invention is illustrated in the accompanying drawing, in which Figure 1 is a view of such parts of the device as are essential to an understanding of the following description of it; Figure 2 is a front view of the indicator hand and dial; Figure 3 is a plan view of the lever contact, the threaded part of the driving shaft and the guide arm;

Figure 4 shows a sectional view of the device hereinbefore more particularly described in which the ratchet, 5, and the spring, 4, are detailed.

In Figure 1, 1 is a shaft, called the driving shaft, such as is found in an ordinary clock but with the addition of a threaded extension, the shaft being shown without supports for the purpose of leaving the drawing more clear, 2 is a gear wheel attached to shaft 1 in such position that it will operate a train of gears, also omitted for the purpose of leaving the drawing more clear, but indicated by the broken lines, connected with gear wheel 13 which drives the 45 shaft on which indicator hand 14 is mounted in such position that it will move over the dial 15 as gear wheel 13 is rotated, a front view of the indicator hand and dial being shown in Figure 2, 3 is a second gear 50 wheel loosely mounted on shaft 1 so that the shaft may be rotated in one direction with-

out moving the wheel but equipped with a ratchet 5, the pawl of which will drag as shaft 1 is rotated in one direction and will lock with and move the gear wheel 3 when 60 the shaft 1 is rotated in the opposite direction, 4 is a coil spring, one end of which is fastened to shaft 1 and the other end to the housing of the device, 6 is the threaded part of shaft 1, 7 is a guide arm with loops to be 65 fitted over shaft 1 at the ends of thread 6 and set at such distance from the threads 6, between the loops, as will allow free movement of lever contact 8 as the threads, by the rotation of shaft 1, force lever contact 8 70 back or forward, towards or away from the position shown by the dotted line 8', 9 is the point at which lever contact 8 is pivoted to its support and to which one wire of an electric circuit is to be connected, 10 is a contact 75 point into which lever contact 8 is to enter and to which the second wire of an electric circuit is to be connected, 11 is a shaft to which is attached two gear wheels, one of which is set in such position that it will be 80 operated on by a train of gears, omitted for the sake of clearness; put in motion by gear wheel 3 as ratchet 5 locks it to shaft 1 when shaft 1 is rotated in the proper direction, the second gear wheel on shaft 11 being connected to an escapement, shown for brevity 85 in the form of a triangle.

In Figure 3, 7 is the guide arm with loops around the shaft, 8 is the free end of the contact lever which moves forward or back 90 as threads 6 are rotated, threads of a large size being shown for clearness.

From the foregoing description it can be seen that as shaft 1 is rotated by a key 95 adapted for that purpose indicator hand 14 will operate by the action of the train of gear wheels and that lever contact 8 will operate by the action of threads 6 and that a proper adjustment of indicator hand 14 will cause it to pass over or leave the zero mark 100 on dial 15 at the very moment lever contact 8 leaves contact point 10 and that as lever contact 8 is forced further from contact 10 by threads 6, indicator hand 14 will be forced to pass over the points on dial 15 105 marked 5, 10, 15 etc. and that as shaft 1 is rotated coil spring 4 will be wound.

It can also be seen that when the winding force applied to shaft 1 is released, coil spring 4 will exert its recoil strength on 110 shaft 1 and cause it to rotate in a direction opposite from that in which it was rotated

by the winding force and that this opposite rotation will force indicator hand 14 to pass over the points on dial 15 in declining sequence, as 30, 25, 20, etc. and that it will 5 also force lever contact 8 to move away from the position indicated by the dotted line 8' towards, and into, contact point 10; the speed of shaft 1, while being driven by the coil spring, and all movements controlled by 10 it as described, being regulated by escapement 12 which may be adjusted so as to allow shaft 1 to force indicator hand 14 over each mark of five on dial 15 in five minutes' time; thus if the winding force is with- 15 drawn from shaft 1 when indicator hand 14 is over the figure 20 on dial 15, twenty minutes will elapse before the zero point on dial 15 is reached by indicator hand 15 and lever contact 8 brought into contact with 20 contact 10.

I am aware that prior to my invention 25 clock movements containing shafts, springs, ratchets, escapements and a combination of gear wheels have been made. I therefore do not claim such a combination broadly.

Having described my invention, I claim:

1. A time lighting device comprising a 30 suitable housing, a shaft, capable of being rotated on its longitudinal axis by power applied to it, and made to force an indicator hand in both a right and left hand rotary direction, depending on the direction of the power applied, a threaded extension on the shaft made to force a lever away from 35 and toward a contact point, depending on

the direction of the power applied to the shaft, the lever held in position to receive the force of the rotating threads in both directions by a guide arm and with the speed of the shaft, while it is being rotated by the 40 recoil power of a coil spring, regulated by an escapement, all substantially as set forth.

2. The combination, in a time lighting device, of a shaft capable of being rotated on its longitudinal axis, in both a right hand 45 and a left hand direction, by power applied at one end of it for rotation in one direction and by the recoil power of a coil spring for rotation in the opposite direction, made to simultaneously force and regulate, by gear 50 wheels, the rotation of an indicator hand both in a right hand and in a left hand direction, and to force and regulate, by means of a threaded extension, the movement of a contact lever, away from and toward a contact point, depending on the direction in which the rotating power is applied, the indicator hand being forced to pass a fixed 55 mark of indication, as the shaft and gear wheels force it in one direction, at the same point of time that the lever contact is forced, by the shaft and threaded extension, to leave a contact point, and also being forced, as the shaft and gear wheels force it in the opposite direction, to return to the same fixed 60 mark of indication at the same point of time that the lever contact is forced, by the shaft and its threaded extension, to return to its contact point, all substantially as described.

EMORY PARSONS.
